CLAIM

The ornamental design for a female charging port connector, as shown and described.

DESCRIPTION

FIG. 1 is left side upper perspective view of a female charging port connector;

FIG. 2 is a right side lower perspective view thereof;

FIG. 3 is a front perspective view thereof;

FIG. 4 is a front view thereof;

FIG. 5 is a rear thereof;

FIG. 6 is a right side view thereof;

FIG. 7 is a left side view thereof;

FIG. 8 is a top view thereof;

FIG. 9 is a bottom view thereof;

FIG. 10 is a section view taken through Section 10-10 in FIG. 7; and,

FIG. 11 is a section view taken through Section 11-11 in FIG. 7.

The broken lines in the drawing illustrate environmental subject matter and form no part of the claimed design.
